UNITED STATES PATENT OFFICE.

PERCY M. ELLIOTT, OF CHICAGO, ILLINOIS; NELLIE S. ELLIOTT, EXECUTRIX OF THE ESTATE OF SAID PERCY M. ELLIOTT, DECEASED, ASSIGNOR TO CAMEL COMPANY, OF CHICAGO, ILLINOIS, A CORPORATION OF ILLINOIS.

RAILWAY-CAR DOOR.

Application filed January 6, 1923. Serial No. 610,962.

To all whom it may concern:

Be it known that I, PERCY M. ELLIOTT, a citizen of the United States, residing at Chicago, in the county of Cook and State of Illinois, have invented certain new and useful Improvements in Railway-Car Doors, of which the following is a specification.

This invention relates to railway car doors constructed of sheet metal sections with 10 marginal reinforce members of structural shapes, and has for its object to provide a door which, while insuring necessary security and durability in use and convenience in applying it to railway cars, will be of 15 simpler construction, of lighter weight, and cheaper to produce than previously known doors.

The invention proceeds upon the principle of making the main body of the door of 20 a plurality of sheets lap jointed together and having distributed over the areas of these sheets, and therefore over the area of the door as a whole, stiffening corrugations at relatively wide distances apart, which 25 leave the main area of the door in a single plane; these corrugations being terminated short of the vertical margins of the door; the top and bottom margins being strengthened by flat reinforcing plates approxi- 30 mately coextensive with the width of the door; and the vertical margins beyond the horizontal corrugations being reinforced by longitudinally corrugated strengthening ribs with continuous longitudinal attaching 35 flanges that embrace substantially the whole area between the ends of the horizontal corrugations and the edges of the door; vertical marginal reinforcing bars being lapped over the top and bottom marginal plates in 40 order to dissipate any line of flexure of the body plates that might develop at the inner edges of the top and bottom marginal plates.

The invention consists of these and other features to be hereinafter described in detail, 45 either severally or in various combinations that are hereinafter pointed out in the claims.

In the accompanying drawings—

Figure 1 is a side elevation of a portion of 50 a freight car having a door embodying in its construction the several features of the present invention.

Figure 2 is a section on the line 2^x—2^x of Figure 1; and

Figure 3 is a section on the line 3^x—3^x of 55 Figures 1 and 2.

1 represents a car body provided with a top guiding and confining rail 2 that receives a hanger or hangers 3 from which to support a door upon said rail, and 4 represents a bottom guide for assisting in confinement of a door relatively to the doorway 5 of the car.

6 represents the door confined by the hanger and bottom guide referred to, in position 65 for sliding into and out of closing relation to the doorway 5. This door comprises a series of plate sections 6^a, 6^b, and 6^c, each having a horizontal dimension equivalent to the width of the door, united by horizontal 70 lap joints 6^x, and collectively developing the height of the door. Each plate section is formed with corrugations 7, preferably two in number, at relatively wide distances apart but sufficient to stiffen the door against distortion on vertically extending lines. These corrugations terminate short of the edges of the door so as to leave vertical marginal portions 8, 9, on the sheets which are substantially covered by single corrugation bars 10 and 11. The corrugation bar 10 has outer attaching flange 12 and inner attaching flange 13 which are riveted to the forward margin of the sheets 6^a, 6^b, and 6^c; and the corrugation bar 11 has inner attaching flange 14 and outer attaching flange 15 riveted to the rear marginal portion of the sheets. The corrugation bars thus made up 80 of a single corrugation with attaching flanges on either side thereof, occupy substantially the entire space between the ends of the corrugations 7 and the front and rear edges of the door, so that they stiffen all those portions of the door which are not stiffened by the horizontal corrugations 7. 95

Moreover, horizontal reinforcing plates 16 and 17, extending across the door respectively at top and bottom thereof, are overlapped by the vertical marginal corrugation bars 10 and 11 in a manner to form with the latter a substantially rectangular frame sustaining the body sheets of the door. The vertical corrugations of bars 10 and 11 terminate short of the top and bottom margins of the door but lap well over on to the reinforcing plates 16—17. At top the hangers 3 are riveted to the reinforce rib 16 at one side of the corrugation bar, and at bot-

22
tom there is left a free space of sufficient vertical dimension to receive the bottom guides. As shown in Figure 2, however, short corrugations or swells 20 are struck up 5 from the lower ends of the corrugation bars 10 and 11, to provide limited face bearings that receive the bottom guides 4 when the door is closed, and cause the door to be pressed into pilfer-proof and weather-proof 10 closure against the face of the door; the cavities left by said swells being closed on the rear by the reinforce plate 17 which thereby prevents escape of small subdivided cargo as well as the introduction of a tool 15 or instrument in an attempt to pilfer.

In addition to the framing and reinforcing members referred to, the front and rear margins are preferably provided with base plates 18, 19 for the rivets which secure the 20 corrugation bars, and the front margin is provided with an angle bar striker 21 while the rear vertical margin is equipped with sealing flange 22, of which the former is held in place by the same rivets 23 that 25 hold the corrugation bar 10 and the riveting plate 18, while the latter constitutes an integral extension of the corrugation bar 11. Corrugation bar 11 sustains the door sheet against flexing stresses on vertical lines, developed 30 by the impingement of the weather-proofing flange 22 against the striker 22a. The shape of the corrugation 11 is particularly effective to this end by reason of the straight form of the rear side of the corrugation and its angular relation to the plane 35 of the door sheet. The angle bar 21 not only provides a strong vertical reinforcing member but, together with the other members at the forward edge of the door, develops 40 a double weather-proofing arrangement, in that it forms a vertically disposed angular air channel between its outstanding flange 21 and the forwardly inclined side of the corrugation 10. This air space helps to deflect 45 rain, dust or other foreign matter which might otherwise enter around the front edge of the door, and the outwardly presented flange affords a convenient means through which to grip the door in opening 50 and closing it.

I claim:

1. A sheet metal car door having a series of widely spaced sheet corrugations with intervening flat sheet areas, said corrugations 55 terminating short of opposite edges of the door a distance sufficient to leave broad flat marginal areas, and corrugation bars secured to a face of the door over said marginal areas extending transversely past the 60 ends of the sheet corrugations; a corrugation bar comprising a single longitudinal corrugation with attaching flanges on either side thereof, and an inner attaching flange lying close to the adjacent ends of the sheet 65 corrugations.

2. A sheet metal car door having a series of widely spaced sheet corrugations with intervening flat sheet areas, said corrugations terminating short of opposite edges of the door a distance sufficient to leave broad flat marginal areas, and corrugation bars 70 secured to a face of the door over said marginal areas extending transversely past the ends of the sheet corrugations; said door having at its respective ends reinforce 75 plates extending parallel to the sheet corrugations and overlapped by the ends of the corrugation bars.

3. A sheet metal car door having a series of widely spaced sheet corrugations with 80 intervening flat sheet areas, said corrugations terminating short of opposite edges of the door a distance sufficient to leave broad flat marginal areas, and corrugation bars secured to a face of the door over said marginal areas extending transversely past the 85 ends of the sheet corrugations; a corrugation bar comprising a single longitudinal corrugation with attaching flanges on either side thereof; there being on the face of the 90 sheet opposite the outer attaching flange of a corrugation bar a plate receiving the ends of the rivets which secure said corrugation bars.

4. A sheet metal car door having a series 95 of widely spaced sheet corrugations with intervening flat sheet areas, said corrugations terminating short of opposite edges of the door a distance sufficient to leave broad flat marginal areas, and corrugation bars 100 secured to a face of the door over said marginal areas extending transversely past the ends of the sheet corrugations; a corrugation bar comprising a single longitudinal corrugation with attaching flanges on either 105 side thereof; a margin of the door being further provided with an angle section strike iron extending parallel to and overlying the outer attaching flange of a corrugation bar and riveted together with the 110 body sheet and said outer corrugation bar flange.

5. A sheet metal car door having a series 115 of widely spaced sheet corrugations with intervening flat sheet areas, said corrugations terminating short of opposite edges of the door a distance sufficient to leave broad flat marginal areas, and corrugation bars secured to a face of the door over said marginal areas extending transversely past the 120 ends of the sheet corrugations; said door having at its respective ends reinforce plates extending parallel to the sheet corrugations and overlapped by the ends of the corrugation bars; the body sheet and its corrugation bars being pressed outwardly to form a swell near an end margin of the door in position to receive a bottom guide.

6. A sheet metal car door comprising a main sheet in the plane of the door con- 130

- structed with a plane rear vertical margin, a vertical reinforcing bar constructed with an angular corrugation and front and rear flanges through which it is riveted to said 5 margin; said reinforced member having an integral weather-proofing flange extending from its rear riveting flange, on the opposite side of the rivets from the corrugation.
7. A sheet metal car door comprising a 10 main sheet having a forward plane marginal portion and reinforcing members on said marginal portion comprising a vertically disposed corrugation bar and a vertically disposed angle bar; the angle bar being riveted to the marginal portion between the corrugation and the forward edge of the door and having an outstanding flange which forms between the flange and the corrugation of the corrugation bar, a 15 vertically extending weather-proofing air pocket.
8. In a sheet metal car door a door sheet, 20 having a plane forward marginal portion, a reinforcing bar constructed with a vertically extending corrugation, and having front and rear flanges riveted to the said
- marginal portion and an angle bar located upon the front flange of the corrugation bar, constructed with an outstanding flange which forms between the flange and the corrugation, a weatherproofing air pocket. 25
9. In a sheet metal car door, a door sheet and a marginal reinforcing member riveted to said door sheet and formed near the lower edge of the door with an outstanding swell 30 in position to receive a door guide and hold the door inwardly against a door frame; the cavity of the swell being closed on the inner side of the door. 35
10. In a sheet metal car door, a door sheet, 40 a reinforcing member on the outer face of said sheet constructed near the lower edge of the door with an outwardly presented struck up swell and said sheet having upon its inner face a reinforcing plate extending 45 across said struck up swell and providing a straight inner surface to that portion of the door.

Signed at Chicago, Illinois, this 3rd day of January, 1923.

PERCY M. ELLIOTT.
